UNITED STATES PATENT OFFICE

FRANCIS J. PLYM, OF NILES, MICHIGAN, ASSIGNOR TO THE KAWNEER COMPANY, OF NILES, MICHIGAN, A CORPORATION OF MICHIGAN

STORE-FRONT CONSTRUCTION

Application filed May 11, 1929. Serial No. 362,366.

This invention relates to store front constructions, and more particularly to the provision of a metallic sash construction, which will be strong, durable and which will readily receive a pane of glass and clamp the edges thereof securely in position.

Among the objects of my invention are to provide a metal setting for plate glass in which the glass is securely held between yieldable metal parts in such manner as to afford simple and efficient means for adjusting and regulating the pressure of the glass along the entire setting, the parts providing a constant tension against the plate of glass, so as to prevent breakage of the pane during the assembly thereof, and after it is being set or placed in position, and to permit vibration, expansion and contraction of the pane without in any way affecting the permanency of the setting. It is desirable in store front constructions, to connect the members which hold the plate of glass with an amount of pressure sufficient to hold the glass firmly in place yet not enough to place the glass under a strain which will make the same susceptible to splitting or cracking when it is subjected to vibration or pressure from external sources, such as those exerted by currents of air, and by persons who may lean against the glass, but at the same time, the setting must be sufficiently yielding so that it will not break at the holding point.

Another object is to provide a sash construction having sufficient ventilation to reduce the accumulation of moisture upon the inner surface of the window, and to provide a gutter or draining means for draining off any condensate or water from the washing of the pane.

A further object is to provide a novel construction of metal sheathing provided with a gutter member. A further object is to provide a construction which does away with the objections of matching the screw holes, thus saving considerable time and energy in the setting of the sash, and window panes.

A still further object is to provide a novel construction of helical screw adapted for tensioning the sash construction after the installation has been made, such construction af-

fording a quick means for setting the sash, the outer member being locked in position from inside of the glass by means of rotation of the screw.

Other objects are to provide a structure of maximum simplicity, efficiency, economy, and ease of assembly and operation, the construction providing a minimum number of parts; and such further objects, advantages and capabilities as will later more fully appear.

My invention further resides in the combination, construction and arrangement of parts illustrated in the accompanying drawings, and while I have shown therein a preferred embodiment, I desire it to be understood that the same is susceptible of modification and change, without departing from the spirit of my invention.

In the drawings:

Fig. 1 is a view in front elevation of a window provided with the novel sash construction.

Fig. 2 is a view in vertical cross section taken on the line 2-2 of Fig. 1.

Fig. 3 is a fragmentary view in vertical cross section taken partly on the line 3-3 of Fig. 2, a portion of the inner or rear member of the sash construction being shown to more clearly disclose the setting.

Referring more particularly to the disclosure in the drawings, the numeral 1 designates a sill or window frame upon which is mounted a metal sheathing 2, preferably of some rust resisting material, and provided with an upwardly projecting flange 3 providing a gutter between the same and the sash construction.

An inner or pane seating section 4, is provided with a base 5, backing member 6 which is doubled upon itself to provide a glass abutting portion, and a shelf or support 7. As shown more clearly in Fig. 2, the base 5 is provided with a raised portion 8 adapted to form a seating portion for seating engagement with the outer sash member or face plate. Small leather blocks 9 are shown as suitably spaced on the lower shelf portion, the present construction of the shelf eliminating the contact of screws with the

edge of the glass and also use of the setting blocks, which were necessary, in the former constructions, where no glass holding or supporting means were provided above the base 5 of the sash construction. Suitably spaced in the backing member are provided openings 10 for the reception of helical screws 11 having spaced threads and provided with a head 12, a shoulder 13, adapted to fit within the opening 11 and a tit or projecting point 14. The slotted heads of the screws 11, are adapted to be engaged by a screw driver or other member for turning the same.

The backing member 6 of the pane seating section is further provided with drain holes 15 and 15^a for draining any condensate or water from the inside of the pane seating section, and for providing a means of ventilation.

20 The threads of the helical screws are adapted to draw inwardly, by a straight longitudinal pull, when the screw head is turned, a face plate 17 having a glass engaging portion 18, and base 19 having an upwardly extending rib or flanges 20, this rib or flange being adapted to be engaged by the spaced threads of the helical screws 11. The outer and downwardly extending portion 21 of the face plate is provided with 25 drain holes 22. These drain holes are suitably spaced along the face plate or moulding, and are adapted, in combination with the drain holes or openings 15 and 15^a of the backing member, to thoroughly drain the 30 sash construction and allow sufficient or adequate ventilation to reduce the accumulation of moisture upon the inner surface of the window. In all sash constructions, it is necessary to have proper ventilation so as 35 to equalize the temperature as near as possible on the inner and outer sides of the pane of glass, to avoid too great or unequal expansion and contraction of the glass.

The present construction does away with 40 all matching of screw holes. The tit or projection 20 of the screws rides over the longitudinally extending rib or flange 20 of the face plate, and allows the screw threads to engage this rib or projection, the construction of the screws providing for the 45 tightening of the inner and outer glass engaging members with a minimum turn of the screw head. In order to properly position the pane seating section, I provide screws or other holding means 23 for suitably attaching this section to the window frame.

The screws 11 also contact with the shelf or glass holding or supporting member 7, and the upper part of the portion 19 of the face 50 plate or moulding, thus preventing collapse of the shelf due to the weight and downward pressure of the pane of glass. The screws are shown as provided with threads of equal diameter. The screws thus have the double 55 function of not only drawing the face plate

longitudinally inwardly so that the edge 18 thereof contacts and holds the glass against the backing member 6, but also to provide a support for the glass. The shelf member 7 prevents any tipping or canting of the face 70 plate, there being thus a flush engagement of the glass engaging portion of the face plate against the glass, preventing any chipping of the edges thereof by contact with the screws or otherwise.

In the assembly of the sash construction, the inner or pane seating section is first placed in position and the attaching means such as screws or the like 23 are driven home. The glass is then placed in position and the face plate or moulding is placed against the glass, the bottom of the face plate or moulding seating on the raised portion 8 of the base 5 of the inner or pane seating section. The screws 11 are then screwed home, the tit 85 or projection 14 thereof riding over the flange 20 and the threads then engaging this flange, thus drawing the flange and face plate or moulding inwardly.

The construction is simple in form and embodies a minimum number of parts which will securely hold the glass and at the same time, allow for the ready removal or replacement of the glass. My invention possesses to the fullest degree, all the characteristics of 95 ventilation, drainage, elasticity and ease of setting which are essential to an efficient window construction.

Having thus disclosed my invention, I claim:

1. In a store front construction, the combination of a pane seating section, a moulding having a longitudinally and upwardly extending rib, and a screw in said section adapted to engage said rib for drawing said moulding into yieldable contacting engagement with a pane of glass, said screw being provided with a projection adapted to ride over and be guided by said rib and spaced threads for engagement therewith.

2. In a store front construction, the combination of a pane seating section, a moulding having a longitudinally extending rib, and a screw in said section adapted to engage said rib for drawing said moulding into yieldable contacting engagement with a pane of glass, said screw being provided with a projecting point adapted to ride over said rib, and spaced threads of equal diameter for engagement with said rib and additionally supporting said pane of glass.

3. In a store front construction, a sill, a pane seating section comprising a sheet of metal bent to form a base anchored to said sill, a backing member for bearing against a pane of glass, and a shelf for supporting said glass; a moulding, a rib on said moulding, and means passing through said backing member and adapted to contact said shelf and engage said rib for drawing said mould-

- ing into firm but yieldable engagement with said pane.
4. In a store front construction, a sill, a pane seating section comprising a strip of metal bent to form a base anchored to said sill, a backing member for bearing against a pane of glass, and a support and protection for the edges of said glass; an outer moulding, the lower portion of said moulding bearing upon said base and provided with a longitudinally and upwardly extending rib, and means passing through said backing member and adapted to engage the edge of said rib for drawing said moulding into engagement with said pane.
5. In a store front construction, a sill, a pane seating section comprising a base anchored to said sill, a backing member for bearing against a pane of glass, and a support for said glass; an outer moulding, the lower portion of said moulding bearing upon said base and provided with a longitudinally and upwardly extending rib, and a threaded member passing through said backing member and the threads thereof adapted to engage the edge of said rib for drawing said moulding into abutting engagement with said pane.
6. In a store front construction, a sill, a pane seating section comprising a strip of metal bent to form a base anchored to said sill, a backing member for bearing against a pane of glass, and a support for said glass; an outer moulding, the lower portion of said moulding bearing upon said base and provided with a longitudinally and upwardly extending rib, and a screw in said backing member and provided with a projection adapted to ride over said rib and the threads thereof to engage said rib for drawing said moulding into contacting engagement with said pane.
7. In a store front construction, a sill, a pane seating section comprising a base anchored to said sill, a backing member for bearing against a pane of glass, and a support for said glass; an outer moulding, the lower portion of said moulding bearing upon said base and provided with a longitudinally and upwardly extending rib, and a screw in said backing member and provided with a projection adapted to ride over said rib and the threads thereof to engage said rib for drawing said moulding into contacting engagement with said pane, the threads of said screw being of equal diameter and engaging the lower portion of said moulding and support for preventing tipping of said screw and sagging or displacement of said support.
8. In a store front construction, a sill, a metal sheathing mounted on said sill and provided with a longitudinally extending rib and a metal sash construction mounted on said sheathing and sill, said rib forming a gutter between the same and said sash construction.
9. In a store front construction, a sill, a metal sheathing mounted on said sill and provided with a longitudinally extending rib, a pane seating section anchored on said sheathing and sill and forming a gutter between the same and said rib, and a moulding positioned on said section and sheathing and adapted to be detachably and adjustably connected to said section for holding a pane of glass therebetween.
10. In a store front construction, a sill, a pane seating section anchored to said sill and comprising a strip of metal bent to form a base, a backing member for bearing against a pane of glass, and a support for holding and protecting the edges of said glass; an outer moulding, the lower portion of which is bent to overlap and contact the base of said section, a longitudinally and upwardly extending rib on said moulding, and a screw member passing through said backing from the inside of the construction and adapted to engage said rib for drawing said moulding into engagement with said pane.
11. In a store front construction, a sill, a pane seating section anchored to said sill and comprising a strip of metal bent to form a base, a backing member for bearing against a pane of glass, and a support for holding and protecting the edges of said glass; an outer moulding, the lower portion of which is bent to overlap and contact the base of said section, and the upper portion adapted to yieldingly engage said glass, a longitudinally and upwardly extending rib on said moulding, and a screw member passing through said backing from the inside of the construction and provided with spaced threads for engaging the edge of said rib for drawing said moulding into abutting engagement with said pane.
12. In a store front construction, a sill, a pane seating section comprising a strip of metal bent to form a base, a backing member for bearing against a pane of glass, and a support for holding and protecting the edges of said glass; means for anchoring said base to the sill, an outer moulding, the lower portion of which is adapted to overlap said attaching means and base and bear upon the latter, a longitudinally and upwardly extending rib on said moulding, and a screw member passing through said backing from the inside of the construction and provided with spaced threads for engaging the edge of said rib for drawing said moulding into abutting engagement with said pane.
13. In a store front construction, a sill, a pane seating section anchored to said sill and comprising a strip of metal bent to form a base, a backing member for bearing against a pane of glass, and a support for holding and protecting the edges of said glass; an

outer moulding, the lower portion of which is bent to overlap and contact the base of said section, a longitudinally and upwardly extending rib on said moulding, and means passing through said section and adapted to engage said rib for drawing said moulding into engagement with said pane, said means contacting said moulding and support for bracing said support against collapse.

10 In witness whereof, I hereunto subscribe my name to this specification.

FRANCIS J. PLYM.
